REGENERATIVE SELECTOR MAGNET DRIVER
William G. Dossé, Chicago, Ill., assignor to Teletype Corporation, Skokie, Ill., a corporation of Delaware
Filed Apr. 9, 1963, Ser. No. 271,623
8 Claims. (Cl. 178—33)

This invention relates to driving circuits for inductive loads and more particularly to a regenerative driving circuit for the coil of the selector magnet in a teletypewriter machine.

In teletypewriter machines currently in use, messages are received in the form of a start-stop code which is comprised of groups of binary "mark" and "space" pulses occurring seriatim. These groups consist of a predetermined number of information pulses encoded in permutation code preceded by a start pulse and terminated by a stop pulse.

The information pulses assume one or the other of two current conditions corresponding to the information they represent; the start pulse always has one of the two current conditions; and the stop pulse always has the other current condition. The stop pulse maintains the coil in an energized condition which continues until a start pulse is received. The start pulse deenergizes the coil, causing the selector magnet to release its armature to initiate operation of the teletypewriter machine. Each of the information pulses, in sequence, causes the selector magnet coil to be energized or deenergized in accordance with the information represented thus causing the armature to be pulled up or released accordingly. After the selector magnet has positioned the armature, mechanical locking levers associated with the selector cams of the teletypewriter machine move above or below the armature (depending on whether a "mark" or "space" pulse is received) to lock the armature into position during the selector interval.

This type of operation is more fully described in United States Patent No. 2,339,313 issued to W. J. Zenner on January 18, 1944.

If the incoming signal is so distorted that it is only accurate at points very near the exact center of each incoming pulse, the mechanical locking levers may not move in time to prevent an error from occurring due to false operation of the selector magnet since the locking levers cannot be economically manufactured with sufficiently close tolerances. This problem is further increased in teletypewriter machines which use a different locking lever for each different pulse or level of the incoming signal group or character, due to the fact that each of these different levers has a different tolerance.

The accuracy of high speed teletypewriter receiving equipment can be increased by using expensive manufacturing techniques to make the tolerances of each of the locking levers the same and to cause these tolerances to be close so that errors of the above type are eliminated. The cost of solving the problem in this manner is prohibitive when presently known manufacturing techniques are used.

Another method for solving this problem caused by distorted received signals is to provide a regenerative repeater at the receiver for reshaping the signal, in a manner well known in the art, before applying it to the selector magnet driver. A disadvantage present in this solution is that a relatively large number of electronic components or relays must be used in addition to those already present in the selector magnet driver thereby making such a solution expensive.

It is an object of this invention to replace the function of the mechanical locking levers and the electronic regenerative repeater with a single electronic circuit which operates both to drive the selector magnet and to

2

hold the armature locked in position until the midpoint of the next incoming pulse.

It is a further object of this invention to combine the features of a regenerative repeater and a selector magnet driver into a single circuit utilizing only a few more components than are necessary for the selector magnet driver alone.

It is yet another object of this invention to provide a regenerative selector magnet driver operated in synchronism with the rotation of the selector cam shaft for rendering the selector magnet driver responsive to the input signals only at the midpoint of each pulse interval, after which, for approximately a full pulse interval, the driver remains set to the condition it attained during the time that the circuit was allowed to be responsive to the input signal.

These and other objects are accomplished in accordance with a preferred embodiment of this invention in which a normally open switch is placed between the source of received telegraph signals and the selector magnet driver circuit. A timing cam having a plurality of notches cut in its periphery is mounted on the selector cam shaft and rotates therewith. The cam follower comprises one of the switch contacts; and whenever the follower encounters one of the notches, the switch is closed momentarily to be reopened by the cam as it continues its rotation. As a result, the input signals are applied to the selector magnet driver only during the brief intervals when the follower contact falls into one of the notches in the cam.

When the switch is closed, the received signal is applied to the energizing circuit for the coil of the selector magnet; and this circuit functions as a conventional Schmitt trigger, well known in the art, to energize and deenergize the coil. Additional coupling elements have been provided in the trigger circuit which cause the circuit to function as a bistable multivibrator whenever the switch contact is reopened by the timing cam. This bistable multivibrator remains set to the stable state which corresponds to the setting of the circuit functioning as a Schmitt trigger just prior to the opening of the contact.

The notches in the timing cam are cut so that the switch is closed at the midpoint of each pulse in each incoming pulse group. Thus, the selector magnet coil remains energized or deenergized in accordance with the received signal present when the switch was last closed throughout each pulse interval until the next closure of the switch which occurs at the midpoint of the next pulse interval. In this manner the signal is regenerated simultaneously as it is used to operate the selector magnet coil, since for the major portion of each pulse interval the system is held nonresponsive to the input signals in the manner of a regenerative repeater. When the input signals are applied to the driving circuit of this invention, they override its operation as a bistable multivibrator causing it to function as a Schmitt trigger circuit.

Further objects and features of this invention will become apparent to those skilled in the art upon consideration of the following detailed description taken in conjunction with the accompanying drawing, the single figure of which shows a circuit diagram of a preferred embodiment of the invention.

Referring now to the drawing, there is shown a pair of line input terminals 10 and 11 to which are applied the incoming or received telegraph signals. For the purpose of this discussion, assume that a "mark" on the line is represented by current flowing on the line and that a "space" is represented by a no current condition. When a mark is present on the line, current flows from terminal 10 through the parallel connection of resistor 12 and a set of diodes called "click suppressors" 13 to terminal 11 thereby causing a voltage drop to take place across the

click suppressors 13 and the resistor 12. Details of the function of these click suppressors are given in the pending application Serial No. 196,384 to C. R. Winston, filed May 21, 1962.

The voltage at the junction 14 between the click suppressors 13 is applied to the base of a transistor 15 through a switch 16 which is operated by a timing cam 17 mounted on the selector cam shaft 18 of a suitable teletypewriter receiver such as the telegraph printer shown in the aforementioned Zenner patent. The portion of the printer described in the Zenner patent which is necessary to an understanding of the invention has been shown in the drawing and includes a selector cam shaft 18, a clutch 19 and the selector cams 20 to which has been added a timing cam 17 in accordance with this invention.

Prior to the receipt of the first group of pulses, the cam shaft 18 is stationary and the timing cam 17 is positioned so that a follower 21 rests on the relatively wide cut out portion 36 of the cam 17. The cut out portion 36 has sufficient width to cause the follower 21 to ride on it during the stop, start, and the first half of the first information pulse of each group. This causes the switch 16 to be closed during this time rendering the drive circuit responsive to input signals as hereinafter explained. When a start pulse is received, it is represented as a "space" or no current condition on the line; so that no potential drop takes place across the click suppressors 13 as a result of line current. This allows the negative potential from the battery 24 to be applied through the now closed switch 16 and the resistor 29 to the base of the transistor 15 causing it to conduct, since this negative potential causes the base of the transistor to be biased negatively with respect to its emitter. When the transistor 15 conducts, the potential on the base of the transistor 23 rises and causes that transistor to be cut off thereby releasing or deenergizing the selector magnet coil 28 in a manner which will be explained more fully hereinafter.

The release of the selector magnet 28 by this action causes the cam shaft 18 to commence rotation as is more fully described in the aforementioned Zenner patent. The follower 21 rides on the cut out portion 36 of the timing cam 17 during the entire start pulse interval and through the first half of the first information pulse of the group, at which time it is raised by the cam 17 to open the switch 16. This causes the selector magnet driving circuit to be nonresponsive to further input signals until the switch 16 is once again closed by the follower 21 falling into the next one of the cut out portions 22 on the timing cam 17.

When the switch 16 is closed by means of the follower 21 falling into one of the slots 22 on the timing cam 17, the voltage present on the terminal 14 is applied to the base of the transistor 15. If there is a mark on the line (current flowing through the click suppressors 13), the voltage on the terminal 14 rises causing the base of the transistor 15 to become positive relative to its emitter, thereby turning the transistor 15 off. This in turn causes the potential on the collector of the transistor 15 to drop thereby biasing the transistor 23 into conduction. When the transistor 23 conducts, current flows from the battery 24 through the common emitter resistor 25, a click suppressor 26, the transistor 23, a current limiting resistor 27, and the energizing coil 28 of the selector magnet to the negative terminal of the battery 24. This causes the coil 28 of the selector magnet to be energized in accordance with a mark appearing on the line between the terminals 10 and 11.

Following this energization, the timing cam 17 continues to rotate in the direction of the arrow with the rotation of the selector cam shaft, causing the follower 21 to open the contacts of the switch 16 thereby rendering the driving circuit, comprised of the transistors 15 and 23, insensitive to further input signals. When this occurs, the circuit comprised of the transistors 15 and 23 operates as a bistable multivibrator or flip-flop due to the cross-

coupling effected by the direct connection between the collector of the transistor 15 and the base of the transistor 23 and the connection between the collector of the transistor 23 and the base of the transistor 15 through a pair of resistors 29 and 30 and a pair of diodes 31. An additional resistor 32 is connected between the positive terminal of the battery 24 and the junction between the resistors 29 and 30 to provide operating bias for the circuit when it functions as a bistable multivibrator. When the signal on the line just prior to the opening of the switch 16 is a mark, as discussed previously, the transistor 15 is turned off and the transistor 23 is rendered conductive. At the time the switch 16 opens, the potential on the collector of the transistor 23 is high and this potential is coupled through the resistors 29 and 30 and the diodes 31 to the base of the transistor 15 to maintain the transistor 15 biased to nonconduction. The driving circuit will remain set to this state until the switch 16 is again closed.

If, at the time the follower 21 falls into the next slot 22 to close the switch 16, the input signal is a space (no current on the line between terminals 10 and 11), the potential on the base of the transistor 15 drops to near the negative potential of the battery 24 causing the transistor 15 to be rendered conductive thereby overriding the bistable circuit characteristics which exist when the switch 16 is open. The circuit now functions as a Schmitt trigger and the rise in potential on the collector of the transistor 15, caused when it becomes conductive, is applied to the base of the transistor 23 and renders it nonconductive due to the fact that the potential on the base of the transistor 23 is driven positive with respect to the potential on the emitter of that transistor.

In order to assume that the transistor 23 is cut off when the transistor 15 is rendered conductive, the click suppressor 26 has been provided in the connection between the emitters of the transistors 15 and 23. This click suppressor causes a slight drop in potential to occur and forces the emitter potential of the transistor 23 to be below the potential applied to its base from the collector of the transistor 15 when the transistor 15 conducts. If the click suppressor 26 were not provided, the potentials on the emitter and base of the transistor 23 would be almost the same when the transistor 15 became conductive; and the transistor 23 possibly might not be rendered nonconductive. The click suppressor 26 prevents this from happening.

When the transistor 23 is rendered nonconductive, the energizing current path for the selector magnet coil 28 is broken causing the selector magnet coil 28 to be deenergized. The selector magnet coil 28 opposes the change in current which has occurred and applies a transient to the collector of the transistor 23 which is more negative than the potential at the negative terminal of the battery 24. This causes a diode 33 to conduct to pass the transient through a resistance capacitance circuit, comprised of a resistor 34 and a capacitor 35, which limits the transient to a value below the breakdown voltage of the transistor 23 while the energy in the coil 28 is being dissipated.

The cam 17 continues to rotate with the selector cam shaft, and the cam follower 21 rises out of the notch 22 opening the switch 16 rendering the circuit nonresponsive to input signals. When this occurs, the circuit once again operates as a bistable multivibrator with the relatively positive potential on the collector of the now conducting transistor 15 applied to the base of the transistor 23 maintaining the transistor 23 in its nonconductive state. The circuit will remain set to this "space" condition until the switch 16 is closed by the action of the follower 21 falling into the next slot 22 which then renders the circuit responsive to the input signal present at that time and causes the circuit to operate as a Schmitt trigger.

The sequence of operation described previously continues throughout each pulse interval of the incoming pulse group or character. The notches 22 cut in the

periphery of the timing cam 17 are spaced so that the switch 16 is closed just prior to the midpoint of each pulse interval and is opened at the midpoint of each pulse interval of the incoming signal. When a complete character has been received, the switch 16 comes to rest in a closed position due to the fact that the follower 21 now rests in the relatively wide cut out portion 36 of the timing cam 17. The switch 16 then remains closed during the stop, start and the first half of the first information pulse of the next group, and the sequence of operation just described is repeated for the next group or character.

The use of this circuit removes the locking control of the selector magnet armature from the inaccurate mechanical locking levers presently in telegraph printers to the relatively accurate control of the timing cam 17. It is possible, with present manufacturing techniques to manufacture the cam 17 with much closer tolerances at a lower expense than it is to manufacture mechanical locking levers with the same close tolerances. The system of this invention reduces errors caused by badly distorted signals in this conventional telegraph printers presently in use in high speed telegraph systems.

The diodes 31 which have been provided in the path coupling the collector of the transistor 23 to the base of the transistor 15 may be eliminated if desired. However, these diodes give a constant voltage drop over a wide range of current flowing through them in the forward direction and compensate for the value of the resistor 30 necessary to provide the proper bias on the base of the transistor 15.

It should be noted that the mechanical switch 16 may be replaced with a photocell or other suitable switching means operated in synchronism with the selector cam shaft 18. The characteristics necessary for such switching means are that under certain conditions it must exhibit a high resistance (open) and under other conditions it must exhibit a low resistance (closed). The use of the term "switch" in the claims is intended to encompass these alternatives.

While this invention has been described in conjunction with a specific embodiment, it will be apparent to those skilled in the art that various modifications and changes may be made in the specific circuit and apparatus shown without departing from the spirit and scope of the invention.

What is claimed is:

1. A regenerative driving circuit for the selector magnet of a telegraph receiver having a timing cam shaft therein including

(a) a source of input signals,
(b) means for energizing the selector magnet in response to input signals above a predetermined magnitude and for causing the selector magnet to be deenergized in response to input signals below the predetermined magnitude,

(c) a normally open switch connected between the source of input signals and the energizing means,
(d) timing means controlled by the rotation of the timing cam shaft for periodically closing the switch to allow the input signal present at the time during which the switch is closed to be applied to the energizing means, and

(e) means operable when the switch reopens for causing the energizing means to remain set to the condition of operation it attained when the switch was closed.

2. A regenerative driving circuit for the selector magnet of a telegraph receiver having a selector cam shaft therein including

(a) a source of binary signals arranged in permutation code,
(b) means for energizing the selector magnet in response to binary signals of one type and for caus-

ing the selector magnet to be deenergized in response to binary signals of another type,

- (c) a normally open switch connected between the source of binary signals and the energizing means,
- (d) timing means controlled by the position of the selector cam shaft for periodically closing the switch to allow the binary signal present at the time of closure to be applied to the energizing means, and
- (e) means operable when the switch reopens for causing the energizing means to remain set to the condition of operation it attained when the switch was closed.

3. Telegraph receiving apparatus having a selector cam shaft and a selector magnet with an energizing coil therein including

- (a) a circuit for energizing the coil of the selector magnet in response to input binary signals,
- (b) a timing cam on the selector cam shaft,
- (c) a switch operated by the timing cam and closed only at predetermined intervals established by the position of the timing cam to render the energizing circuit responsive to the input signals, the energizing circuit operating as a Schmitt trigger when the switch is closed, and
- (d) means for causing the energizing circuit to operate as a bistable multivibrator when the switch is open, the energizing circuit being set to the stable state which corresponds to the setting of the circuit functioning as a Schmitt trigger just prior to the time the switch is opened.

4. A regenerative driving circuit for the selector magnet of a telegraph receiver having a selector cam shaft therein including

- (a) a source of input signals,
- (b) a circuit operating as a Schmitt trigger for energizing the selector magnet in response to input signals above a predetermined magnitude and for causing the selector magnet to be deenergized in response to input signals below the predetermined magnitude,

(c) a normally open switch connected between the source of input signals and the energizing circuit,

- (d) timing means operated in synchronism with the rotation of the selector cam shaft for periodically momentarily closing the switch to allow the input signal present during the time the switch is closed to be applied to the energizing circuit, and

(e) means operable when the switch reopens after each closure for causing the energizing circuit to function as a bistable multivibrator remaining set to the condition the circuit attained when the switch was closed.

5. Apparatus according to claim 4 in which the input signals are binary signals arranged in permutation code.

6. A regenerative driving circuit for the selector magnet of a pulse communication receiver having a selector cam shaft therein including

- (a) a source of binary input pulses arranged in permutation code,

(b) a circuit for energizing the selector magnet in response to input binary pulses having a magnitude above a predetermined level and for causing the selector magnet to be deenergized in response to input pulses having a magnitude below the predetermined level,

(c) a normally opened switch connected between the source of input signals and the energizing circuit,

- (d) a timing cam operated in synchronism with the rotation of the selector cam shaft for periodically momentarily closing the switch once during each binary pulse to allow the input signal present during the time the switch is closed to be applied to the energizing circuit, and

(e) means operable when the switch reopens after each closure thereof for causing the energizing cir-

cuit to remain set to the condition the circuit attained during the time the switch was closed.

7. A system in accordance with claim 6 wherein the energizing circuit functions as a Schmitt trigger when the switch is closed and functions as a bistable multivibrator when the switch is open. 5

8. A regenerative driving circuit for the selector magnet of a telegraph receiver having a selector cam shaft therein including

- (a) a source of binary pulse input signals arranged 10 in permutation code,
- (b) a circuit operating as a Schmitt trigger for energizing the selector magnet in response to input pulses of one type and for causing the selector magnet to be deenergized in response to input pulses of a 15 second type,
- (c) a normally open mechanical switch connected between the source of input pulses and the energizing circuit,
- (d) a timing cam operated in synchronism with the 20 rotation of the selector cam shaft and having a plurality of slots cut in the periphery thereof for per-

iodically momentarily closing the switch once during each input pulse to allow the input pulse present during the time the switch is closed to be applied to the energizing circuit setting it in accordance therewith, and

(e) additional means operable only when the switch reopens following each momentary closure for causing the energizing circuit to function as a bistable multivibrator remaining set to the condition the circuit attained through the time the switch was closed.
